UNITED STATES PATENT OFFICE.

JAMES C. STEEN, OF CINCINNATI, OHIO, ASSIGNOR TO THE CINCINNATI SHAPER COMPANY, OF CINCINNATI, OHIO, A CORPORATION OF OHIO.

SHAPING-MACHINE.

No. 807,404.

Specification of Letters Patent.

Patented Dec. 12, 1905.

Application filed April 13, 1904. Serial No. 202,943.

To all whom it may concern:

Be it known that I, JAMES C. STEEN, a citizen of the United States, and a resident of Cincinnati, in the county of Hamilton and State 5 of Ohio, have invented a certain new and useful Improvement in Shaping - Machines, of which the following is a full, clear, and exact description, reference being had to the accompanying drawings, which form a part of my 10 specification.

My invention relates to shaping-machines, and more particularly to that class of shaping-machines having a traveling head or carriage. It may be applied to one having either one or 15 two carriages.

The object of my invention is to produce a shaping-machine of the class described with the traveling head or carriage so constructed and arranged and the feeding mechanism so 20 related thereto that the ram may be adjusted to travel at any horizontal angle with the direction of travel of the carriage without in any way interfering with the horizontal feed or travel of the carriage along the bed of the 25 machine.

The various advantages of my improvement will appear as I proceed with my specification.

In the drawings, Figure 1 is a top plan view showing the traveling head or carriage and 30 one end of the bed or frame of the machine. Fig. 2 is a side elevation, and Fig. 3 is a front elevation, of the same. Fig. 4 is a top plan view of the carriage with the parts resting thereon removed and broken away in several 35 places to show details of gearing. Fig. 5 is a vertical section on the line 4 4 of Fig. 4. Fig. 6 is a partial vertical section through the housing of the shaft N, as indicated by the line 6 6 in Fig. 1. Fig. 7 is a vertical section 40 through the carriage on the line 7 7 of Fig. 4. Fig. 8 is a section on the line 8 8 of Fig. 5, showing the gears, sleeve, ratchet, and ratchet-lever in elevation. Fig. 9 is a vertical section through the carriage on the line 9 9 45 of Fig. 4, and Fig. 10 is a detail on a large scale of the adjusting-sleeve e.

A is the bed-plate and frame of the machine. B is the table, and C the carriage, these parts being of the usual construction.

50 Supported on suitable bearings near the top of the frame are the screws A' A'', upon which work the nuts attached to the carriages, by which the same are caused to travel backward and forward over the frame in the usual

manner. The carriage C supports a revolute 55 saddle D, which carries the ram, the driving-arm, the motor, and the various mechanisms by which the parts on the saddle are operated. The upper face of the carriage and the lower face of the saddle D are milled down so as to 60 present bearing-surfaces to each other, and are provided with annular keyways C' (see Fig. 9) in which fits an annular key C'', which serves to center the saddle D and maintain its axis of rotation constant. The upper face of 65 the carriage C is also provided with an annular T-slot e, in which fit the heads of bolts e', which pass through holes in the saddle D and which are provided with nuts e'', by means of 70 which the saddle D is locked securely in any horizontal angular position.

E is the ram, which travels in guideways E' on the saddle D in the usual manner.

The power for driving the mechanism is obtained from a motor F, which is in any 75 suitable manner supported on and secured to the saddle D.

G is the controller-box, and G' a hand-wheel governing the same.

The motor, through gears H H' and a set of 80 variable speed-gears J, J', J'', and J''', the shaft K, and the pinion K', all suitably supported in any usual manner, as shown in the drawings, drives the gear K'', to which is secured the driving-arm L, which through the 85 pitman L' reciprocates the ram E. There is nothing unusual in this construction and it requires no special description except to say that the bearings are all supported on the saddle D. 90

The power-feed for causing the saddle to move from one point of the bed to another is accomplished by the following mechanism: The end of the motor-shaft F' is provided with a spiral gear M', which engages with another 95 spiral gear M'', keyed to a shaft N. The shaft N has its bearing at one end in the housing M''', which is supported on the bracket N', in which housing the motor-shaft also has bearing and which covers in the spiral gears M' 100 M''. The other end of the shaft N has its bearing in a housing N'', supported on the saddle D. A spiral gear O is there loosely mounted on the shaft N, (see Figs. 5, 6, and 8,) said spiral gear having a long hub O', 105 which projects through the housing and has clutch-teeth adapted to be engaged by similar teeth on clutch O'', which is splined to N and

adapted to be engaged with or disengaged from the hub O' by mechanism to be described later. Journalized in the housing N" below the gear O is a short shaft P, having keyed to it at one end a spiral gear P', engaging the spiral gear O, and at the other end a spur-gear P'', engaging a spur-gear P''', keyed to a shaft P⁴. The spur-gear P''' engages spur-gear Q, keyed to a shaft Q', journalized in the plate D, and a second spur-gear Q'' is keyed to said shaft Q' and engages a spur-gear R, keyed to a shaft R', which is supported in suitable bearings from the saddle D and which carries at its other end a spiral gear R''. (See Figs. 4, 7, and 9.) The latter engages a spiral gear S, keyed to a short vertical shaft S', which is supported in the carriage C with its axis coincident with the axis of rotation of the saddle D and carries at its lower end on the under side of the carriage a miter-gear S''. A horizontal shaft T is hung below the carriage and is provided at one end with a miter-gear T', engaging the miter-gear S'', and at the other end with a spur-gear T'', which engages a spur-gear T''' on the usual nut U, through which the screw A' works and which is secured to the under side of the carriage in the usual manner. It is thus apparent that when the clutch O'' is caused to engage with the hub O' of the gear O that the rotation of the motor-shaft will be communicated through the spiral gears M' M'' to the shaft N, thence through the spiral gears O P', the shaft P, the spur-gears P'', P''', and Q, the shaft Q', the spur-gears Q'' R, the shaft R', the spiral gears R'' S, the vertical shaft S', coincident with the axis of rotation of the plate D, through the bevel-gears S'' T', the shaft T and the spur-gear T'' to the spur-gear T''' on the nut U, which is thus caused to rotate and travel on the screw A and carry with it the carriage. It is also apparent that as the shaft S' is in the axis of rotation of the saddle D the carriage may be moved with the saddle D in any horizontal angular position without throwing out or disarranging any of the gearing above described.

When it is desired to feed the tool, as when it is doing work, the clutch O'' is disengaged, which leaves the spiral gear O free to turn loosely on the shaft N, the rotation of that shaft then having no effect on said gear. The feeding mechanism is then driven through the shaft P⁴ and the spur-gear P''' in the following manner: The shaft P⁴ is prolonged beyond the housing N'', where it has keyed to it a ratchet-wheel e'. A sleeve e is loosely mounted on a boss on the housing N'', which forms the bearing of the shaft P⁴, and said sleeve is provided with a projecting flange e'', (see Figs. 1, 3 and detail 10,) which has a portion of its circumference cut away, as illustrated in Fig. 10. Said flange e'' is adjacent to the ratchet-wheel e' and is adapted to be engaged by a pin e''', carried by a spring-

controlled pawl f, pivoted to a rocker-arm g, which is journaled on the shaft P⁴. The sleeve is milled except for a short distance from its end nearest the housing N'', where it is smooth and is provided with a notch f', adapted to be clutched by a detent on one arm f'' of a bell-crank lever f''', which is pivoted to an extension of the housing N''. The other arm f⁴ is pivotally connected to a segment f⁵, which bears in an annular groove f⁶ in the clutch O''. The handle f⁷ operates the bell-crank lever f'''. It is apparent that the ratchet-wheel e' can only be engaged by the pawl f when the sleeve e is so turned that the pin e''' bears upon that part of the flange e'' which is cut away and that the effective throw of the pawl can be readily controlled by means of this sleeve, this being the usual construction and forming no part of this invention. The notch f' is in such a position with reference to the cut-away portion of the flange e'' that it can only be engaged by the detent on the arm f'' of the bell-crank f''' when the sleeve e is in position to prevent the pawl f from engaging the ratchet-wheel e'. The bell-crank lever f''' can be thrown so as to cause the clutch O'' to engage the sleeve O' only when the notch f' is in a position to receive the detent on the arm f'' of the bell-crank lever. Therefore one mechanism cannot be thrown in until the other is made completely inoperative. The rocker-arm g is rocked in the usual manner by a pitman h, pivotally connected to and operated by the crank h', secured to the driving-arm L in the usual manner.

My invention and also its operation will be understood from this description.

I do not wish to limit myself to the exact details of construction, as it is apparent that other gearing may be substituted for that shown and described. The construction as shown permits the saddle to be adjusted at any horizontal angular position without in any way interfering with the longitudinal travel of the carriage, and the carriage may be fed along the bed either rapidly, as through the shaft N, or intermittently, as when feeding through the driving-arm L, entirely independent of the horizontal angle of the saddle to the bed. The bell-crank lever f''' also provides a safety device for throwing either one of these driving mechanisms into operation and is so constructed that when one is in the other is out, thus preventing any possibility of breakage.

Having thus described my invention, what I desire to claim as new and to cover by Letters Patent is—

1. In a shaping-machine, in combination with the bed-plate, feed-screw, rotatable nut thereon, and traveling carriage, a rotatable saddle bearing on said carriage, means for locking said saddle in any angular position, the ram, motor, driving-shaft and driving-arm

carried by said rotatable saddle and mechanism intermediate said driving-shaft and said rotatable nut adapted to rotate the same irrespective of the angular position of said rotatable plate, substantially as described.

2. In a shaping-machine, in combination with the bed-plate, feed-screw, rotatable nut thereon and traveling carriage, a rotatable saddle bearing on said carriage with means for locking the same in any angular position, the motor, driving-shaft, ram and driving-arm carried by said saddle, a second shaft journaled in said carriage with its axis coincident with the axis of rotation of said rotatable saddle, mechanism supported by said saddle intermediate said driving-shaft and said second shaft, and mechanism supported by said carriage intermediate said second shaft and rotatable nut, adapted to rotate the same, substantially as described.

3. In a shaping-machine, in combination with the bed-plate, feed-screw, rotatable nut thereon and traveling carriage, a rotatable saddle bearing on said carriage with means for locking the same in any angular position, the motor, driving-shaft, ram and driving-arm carried by said saddle, an intermediate shaft, supported on said saddle and adapted to be driven either continuously from the driving-shaft or intermittently from the driving-arm, a clutch adapted to at the same time couple with the one and uncouple with the other, a vertical shaft journaled in the carriage, together with mechanism between said intermediate shaft and said vertical shaft carried by said revoluble saddle and mechanism intermediate said vertical shaft and said nut adapted to revolve the latter, substantially as described.

4. In a shaping-machine, in combination with the bed-plate, feed-screw, rotatable nut thereon and traveling carriage, a vertical shaft with bearing in said carriage and mechanism adapted to communicate its rotation to said rotatable nut, a rotatable saddle bearing on said carriage with means for locking the same in any angular position, the ram, motor, driv-

ing-shaft, and driving-arm carried by said rotatable saddle, an intermediate shaft supported on said rotatable saddle with mechanism connecting said shaft with said vertical shaft 50 adapted to rotate the latter, said mechanism being supported on said revoluble saddle, mechanism supported by said revoluble saddle between said driving-shaft and said intermediate shaft and between said driving-arm 55 and said intermediate shaft, clutching devices adapted to operatively connect said intermediate shaft with either of these, and a clutch-operating device adapted to lock either mechanism in inoperative position when the other 60 is in operative position, substantially as described.

5. In combination, a revoluble shaft, a continuously-rotating shaft at an angle thereto, a gear loosely mounted on said continuously-revolving shaft with its hub provided with clutch-teeth, gearing intermediate said loosely-mounted gear and said revoluble shaft, a clutch member feathered to said continuously-revolving shaft adapted to engage the hub of said loosely-mounted gear, a ratchet-wheel keyed to said revoluble shaft, a rocker-arm and spring-controlled pawl carried thereby adapted to engage said ratchet-wheel, with means for rocking the same, a flanged sleeve controlling the active throw of said spring-controlled pawl, a notch in said sleeve, a bell-crank lever pinioned adjacent said revoluble shaft, one arm adapted to operate said clutch member and the other arm bearing on said flanged sleeve and adapted to enter said notch therein, and permit said clutch member to be thrown into engagement with the hub of said loosely-mounted gear when said flanged sleeve is in position to prevent the pawl from engaging said ratchet-wheel, substantially as and for the purpose described.

JAMES C. STEEN.
